UNITED STATES PATENT OFFICE

2,348,456

FEEDING MECHANISM

Hubert E. Dickerman, Springfield, Mass.

Application December 8, 1942, Serial No. 468,205

5 Claims. (Cl. 271—2.5)

This invention relates to improvements in feed mechanism and is directed more particularly to feed mechanism of the type disclosed in United States Letters Patent No. 2,188,473 issued to me on January 30, 1940.

The principal objects of this invention are directed to the provision in a feed mechanism such as shown in the above-mentioned patent, of means for separating the rolls of the pairs thereof in predetermined relative positions of the pairs of rolls.

Oftentimes, in the feeding of strip material, due to the action of the dies being fed with the strip or to the characteristics of the strip material or to various other causes, there is a tendency for the strip to crowd laterally or move out of alignment with the die members in one direction or the other which impairs the operation.

According to this invention, the rolls of a pair are separated at a certain time of each cycle of operation, or at some predetermined relative position of the pairs of rolls whereby the material being fed may, when out of alignment with the die, be moved into the desired operating alignment thereby to obtain the desired accuracy and efficiency of operation. The rolls may be separated to release the material being fed by the action of the feed mechanism or by the operating means therefor, all as may be desired.

The feeding apparatus of the invention is characterized by a novel combination and arrangement of parts to the end that the construction is efficient in operation, easily and readily adjustable within wide limits to suit various conditions of usage, and operates with a positive action for the purpose intended.

The various novel features and advantages of the invention will be hereinafter observed in connection with the description of the present preferred form thereof, reference being had to the accompanying drawings, wherein:

Fig. 1 is a plan view of a feeding mechanism embodying the novel features of the invention;

Fig. 2 is a side elevational view of the feed mechanism shown in Fig. 1;

Fig. 3 is an enlarged sectional elevational view on the line 3—3 of Fig. 1;

Fig. 4 is a similar view on the line 4—4 of Fig. 1;

Fig. 5 is a small scale perspective view of a cam member which may be used with the mechanism shown in Figs. 1 and 2;

Fig. 6 is a small scale diagrammatic view to explain certain features of the invention;

Fig. 7 is a fragmentary side elevational view

illustrating how the shafts are held against rotation;

Fig. 8 is a cross sectional view through one of the shafts and rolls having means associated therewith to prevent rotation of the shaft in one direction;

Fig. 9 is a sectional elevational view on the line 9—9 of Fig. 1 showing one form of means for separating the rolls of the feeding mechanism;

Fig. 10 is a plan view of mechanism for yieldingly holding the rolls of a pair in operable engagement;

Fig. 11 is an end elevational view of the mechanism shown in Fig. 10; and

Fig. 12 is a side elevational view of the mechanism shown in Figs. 10 and 11.

With reference now to the drawings more in detail, the invention will be fully described. It will be understood that various changes and modifications may be made in the form of the mechanism without departing from the spirit and scope of the invention.

The following description refers to the feeding of a strip of material to a die set but within the broad scope of the invention the mechanism is adapted for use in connection with various machines or tools and for feeding stock in various forms for various and numerous purposes.

25 30 Upper and lower die members of a die set are represented by 2 and 4 and these may carry various cooperating tools or devices which, as the said members 2 and 4 move toward and away from one another, act or work on the stock and perform various operations. The mechanism of the invention in the form thereof to be described is adapted to feed successive portions of strip material thereto for successive operations.

35 40 A base or support 6 has spaced longitudinal guides 8 extending from a part 10 which may be formed in any suitable manner for securing the mechanism to a machine or to one of the members of a die set, such as the member 4. The outer ends 12 of the guides, in the present form of the invention, extend inwardly towards one another more or less and are connected by a transverse member 14.

45 50 The extremities 16 of the guide are turned outwardly away from one another to provide lugs, as shown. A carriage indicated generally by 20 is reciprocable back and forth on the guides 8 and carries a pair of cooperating rolls, as will be hereinafter described.

55 The extremities 16 of the guide are turned outwardly away from one another to provide lugs, as shown. A carriage indicated generally by 20 is reciprocable back and forth on the guides 8 and carries a pair of cooperating rolls, as will be hereinafter described.

A transverse shaft 22 extends between the members 12 and is secured therein against rotation by

any suitable means, such as by caps 24 having a set screw or screws 22', see Fig. 7. The upper sides of members 12 are provided with vertically disposed slots 26.

Blocks such as 28 are movable up and down in said slots and a cap 30 extends between and is secured to the members 12. It has in threaded engagement therewith at opposite ends adjusting screws 34 which are provided with manually engageable members 36.

Springs 38 bear on the blocks 26 so that by rotating the screws in one direction or the other the compression of the springs may be varied to cause them to yieldingly bear on the blocks with more or less pressure as may be desired. A shaft 40 is secured at opposite ends against rotation in the block in any suitable manner as by set screws 40', see Fig. 7. The shafts 22 and 40 have rolls 86 and 88 rotatable thereon, each in one direction all as will be hereinafter described.

A transverse carriage member 42 between guides 8 has upstanding side portions 44 disposed adjacent inner sides of guides 8. Plates 46 on the outer sides of the said guides 8 and secured to the parts 44, are so arranged as to cooperate therewith, and form carriage 20 slideable on the guides 8.

A lower shaft 48 similar to shaft 22 is fixed in the members 44 against rotation and the upper ends of the members 44 are provided with vertically disposed slots 50. In these slots are blocks, similar to the blocks 28 that are slideable up and down in slots 26 and a shaft 43 is carried by said blocks. A cap member 52 secured to parts 44 and similar to the cap 30 has screws 54 in threaded engagement therewith which carry manually engageable members 56. Springs 58 similar to the springs 38 yieldingly bear on the blocks in the slots 50. The shaft 48 is secured against rotation in parts 44 similarly to the shaft 22 and shaft 43 is secured in the blocks similarly to shaft 40, as shown in Fig. 7.

Ears 60 extend outwardly from the plates 46 and rods 62 have their ends fixed therein in some suitable manner. The lugs 16 at the outer end of the support slidably receive the outer ends of the rods 62 which are provided with screw threads 64 as shown.

Lock nuts 66, which may be of any suitable form, are in threaded engagement with the threaded ends 64 of the rods 62 and a tube 68' may rather loosely embrace the rods to protect the threaded portions thereof. Springs 68 around the rods 62 extend from the ears 60 to the lugs 16 and are arranged and adapted to move the carriage 20 inwardly or to the left after it has been moved to the right, as well as to yieldingly resist movements of the carriage to the right.

A cam member 74 may be secured in some suitable manner to the member 2 of the die set and it has end portions provided with actuating faces and dwell faces 76 and 78. The parts are so arranged that as the upper die set member moves downwardly towards die member 4, the cam faces 76 act on rolls 80 of the carriage to bring about movement of the carriage relative to the support, in a direction to the right towards the outer end of the support.

This movement of the carriage is against the action of the springs 68 and when the die member 2 moves upwardly and rolls 80 ride off from dwell faces 78 the carriage moves to the left from the position shown in Fig. 1.

A guide or guides such as 82 are provided in association with the support 6 at the left hand end thereof which as the die member 2 moves downwardly engage or operate against the surfaces or

parts 84 of the cam member 74. The guide or guides 82 serve to steady the parts which makes for rigidity and accuracy.

The carriage in Fig. 1 is shown in a position adjacent the outer end of the support which may be called the strip gripping position. A position at the left thereof may be called the feeding position. The nuts 66 may be adjusted so that the movement of the carriage 20 between feeding and gripping position may be varied to vary the length of the strip portion being fed to the die members.

As has been stated there is a pair of rolls 86 and 88 on the shafts 22 and 48 and there is a pair of rolls 90 and 92 on the shafts 48 and 43. These rolls are mounted in some suitable manner on their respective shafts, as by pin bearings, for free rotation in one direction only while they are held against rotation in an opposite direction by some suitable means such as clutches, pawls, or the like.

A well known form of construction is shown in Fig. 8 wherein pawls 106 in the form of cylinders are disposed in longitudinally extending radially disposed slots in a shaft such as 22 as shown are arranged to lock a roll such as 86 when it is attempted to rotate the roll clockwise. Flat springs 110 may be employed to urge the pawls to engage the roll and shaft while the roll on rotation in a counterclockwise direction merely acts on the pawls to move them from engaging position.

In the form of the invention being described, the rolls 86 and 92 are freely rotatable in a clockwise direction and held against rotation in opposite directions. Rolls 86 and 90 are freely rotatable in a counterclockwise direction and held against rotation in opposite directions.

According to the constructions described, the strip of material first passes between the rolls 86 and 88 which rotate as above described. As the carriage moves to the right to gripping position, the rolls 86 and 92 are held against rotation in such a way that they hold the strip against movement to the right.

During the travel of the carriage to the right as aforesaid, the rolls 90 and 92 rotate freely in the direction above described and roll along the strip. When the carriage reaches the limit of its stroke in gripping position and moves to the left to feeding position the rolls 90 and 92 are held against rotation as above described so as to grip or engage the strip and feed it to the left. During the feeding movement the rolls 86 and 88 permit feeding of the strip since they are free to rotate when the carriage is carrying the strip towards the die set.

In each stroke of the carriage between gripping and feeding positions and according to the arrangement and adjustment of the parts, the strip is advanced or fed a desired amount or length to present successive portions or sections thereof to the die set.

The screws 34 and 54 may be adjusted for the desired pressure. The rolls function with a rolling action to permit relative movements of the pairs of rolls and strips so that by their yielding coaction strips which may be wavy and of uneven thickness may be fed in predetermined lengths.

Guide members 94 are pivoted at 96 to the transverse member 14 and carry rolls 98 on their ends which may be grooved or otherwise formed to receive and guide stock into rolls 86 and 88. Slots 100 in members 94 receive clamp bolts 102.

in threaded engagement with member 14 which hold the members in adjusted positions to accommodate stock or strips of various widths.

Levers 110' are pivoted on the shaft 43 at opposite ends of roll 92 and where used the said roll 92 is slightly less in face than the roll therebelow. The said lever 110' has a tongue part 112 which is adapted to pass beneath the shaft 40 of the roll 88.

Studs 114 project from the members 44 and the levers 110' have adjusting screws 116 in threaded engagement therewith for abutting the said studs 114. Cam faces 118 of the levers 110' are arranged to engage the shaft 40 and cam it upwardly at the proper time.

The adjusting screws 116 are provided to raise and lower the levers and thereby vary the action of the cam faces on the shafts 40.

In the form of the invention shown, the cam faces 118 engage the shaft 40 when the pairs of rolls are in a certain relative position so as to elevate roll 88 and in further movement of the rolls 90 and 92 towards the rolls 86 and 88 the screws 116 on the studs act as fulcrums so that the pivoted end of lever 110' elevates roll 92 to separate it from the roll 90.

The parts may be constructed and arranged to elevate the upper rolls in any desired position of the pairs of rolls thereby to release the material between the rolls so that it may assume the desired position. In some cases it may be desired to separate the rolls of the pairs simultaneously or to separate the rolls of one pair before those of the other pair are separated and the separation may take place at any desired position of the dies or other mechanism to which material is being fed.

In other cases it may be desired to operate the separating means from the member 74 or from the relatively movable parts to which the material is being fed, all within the scope of the invention.

In lieu of the cap members 30 and 52, it is desired to employ cap members such as 120 that have spaced ribs 122. A plate 124 guided for up and down movement between the ribs 122 and a lever 126 is pivoted at 128 between the ribs of the cap.

Screws 130 in threaded engagement with the bar 124 at its opposite ends act on springs 132 that yieldingly bear on the blocks 26 for the shaft 40.

The lever 126 and its pivotal connection with the cap are constructed and arranged so that when in lower clamping position there is an eccentric action to cause the lever to be releasably locked in this position. The lever acts on the members 124 which in turn through screws 132 causes the springs to yieldingly bear on the blocks 26 whereby the upper roll is yieldingly urged towards the lower one.

The upper roll may be quickly released by swinging the lever 126 upwardly from the position shown. The upper roll is quickly released and consequently material between the rolls is released.

The tension of springs 132 may be varied by movement of the screws 130 thereby to obtain the desired yieldable pressure between the rolls according to material being fed, or for other reasons.

Altogether it is possible to separate the rolls manually or automatically as may be desired to facilitate adjustment of the material being fed

or to enable it to become adjusted in each cycle of operation of the mechanism.

While I have described the invention in great detail and with respect to the present preferred form thereof, it is not desired to be limited thereto since many changes and modifications may be made therein without departing from the spirit and scope of the invention. What it is desired to claim and secure by Letters Patent of the

United States is:

1. The combination with relatively reciprocable members movable towards and away from one another of feed mechanism comprising, a support adapted to be secured to one of said members, a carriage guided for straight line movements back and forth thereon, a cam on one of said members engageable with said carriage to move the same in one direction on the support as the members move relative to one another in one direction, pairs of rolls on said carriage and on said support for receiving therebetween a strip of material, yielding means to hold the rolls of the pairs in relatively yieldable engagement, means for permitting free rotation of the rolls in certain directions and holding them against rotation in other directions, means to move the said carriage in an opposite direction as the carriage is disengaged by said cam, and roll separating means operating to overcome the yielding means and separate the rolls of one pair when the pairs of rolls are in a certain predetermined position.

2. The combination with relatively reciprocable members movable towards and away from one another of feed mechanism comprising, a support adapted to be secured to one of said members, a carriage guided for straight line movements back and forth thereon, a cam on one of said members engageable with said carriage to move the same in one direction on the support as the members move relative to one another in one direction, pairs of rolls on said carriage and on said support for receiving therebetween a strip of material, yielding means to hold the rolls of the pairs in relatively yieldable engagement, means for permitting free rotation of the rolls in certain directions and holding them against rotation in other directions, means to move the carriage in an opposite direction as the carriage is disengaged by said cam, and means to separate the rolls of the pairs of rolls when said pairs of rolls are in a certain predetermined position, said means including a member pivoted on one roll of one pair having a part for engaging the corresponding roll of the other pair.

3. The combination with relatively reciprocable members movable towards and away from one another of feed mechanism comprising, a support adapted to be secured to one of said members, a carriage guided for straight line movements back and forth thereon, a cam on one of said members engageable with said carriage to move the same in one direction on the support as the members move relative to one another in one direction, pairs of rolls on said carriage and on said support for receiving therebetween a strip of material, yielding means to hold the rolls of the pairs in relatively yieldable engagement, means for permitting free rotation of the rolls in certain directions and holding them against rotation in other directions, means to move the carriage in an opposite direction as the carriage is disengaged by said cam, and means to separate the rolls of the pairs of rolls when said pairs of rolls are in a certain predetermined position, said means including

members pivoted on one roll of the pair of rolls on said carriage having parts engaging the corresponding roll of the other pair.

4. The combination with relatively reciprocable members movable towards and away from one another of feed mechanism comprising, a support adapted to be secured to one of said members, a carriage guided for straight line movements back and forth thereon, a cam on one of said members engageable with said carriage to move the same in one direction on the support as the members move relative to one another in one direction, pairs of relatively yieldable rolls on said carriage and on said support for receiving therebetween a strip of material, means for permitting free rotation of the rolls in certain directions and holding them against rotation in other directions, means to move the carriage in an opposite direction as the carriage is disengaged by said cam, and means to separate the rolls of the pairs of rolls when said pairs of rolls are in a certain predetermined position, said means including levers pivoted to the upper roll of the pair of rolls of the carriage having a cam part for engaging beneath the corresponding roll of the other pair and means as-

10 associated with said levers and carriage adapted for engagement to act as fulcrums for said levers when engaging said corresponding roll.

5. The combination with relatively reciprocable members movable towards and away from one another of feed mechanism comprising, a support adapted to be secured to one of said members, a carriage guided for straight line movements back and forth thereon, a cam on one of said members engageable with said carriage to move the same in one direction on the support as the members move relative to one another in one direction, pairs of yieldingly mounted rolls on said carriage and on said support for receiving therebetween 15 and yieldingly engaging a strip of material, means for permitting free rotation of the rolls in certain directions and holding them against rotation in other directions, means to move the carriage in an opposite direction as the carriage is disengaged by said cam, and means operable by the position of the rolls to overcome the yielding engagement of the rolls of the pairs of rolls when said pairs of rolls are in a certain predetermined relative position.

HUBERT E. DICKERMAN.
